ATTORNEY

UNITED STATES PATENT OFFICE.

ANNIE SHERIDAN, OF NEW YORK, N. Y.

HAIR-CURLER.

SPECIFICATION forming part of Letters Patent No. 716,295, dated December 16, 1902.

Application filed March 21, 1902. Serial No. 99,322. (No model.)

To all whom it may concern:

Be it known that I, ANNIE SHERIDAN, a citizen of the United States, residing in the city, county, and State of New York, have invented 55
5 certain new and useful Improvements in Devices for Producing Wavy Hair, of which the following is a specification.

This invention relates to appliances or implements for dressing the hair; and it has 10 for its object a device for producing what are known as "waves" in the hair, imitating the natural waviness therein, as distinguished from devices for curling the hair. In producing curls the hair is wrapped or wound 15 spirally about some object and either heated while so wound or secured and held in the tightly-wound condition for a considerable time. For producing waviness in the hair a flat lock of the same is put into a zigzag form 20 edgewise of the lock and held in that form until it acquires a set.

My appliance or device is designed to accomplish the last-named object.

In the accompanying drawings, which illustrate an embodiment of the invention, Figure 25 1 is a plan of the device represented in its normal condition and ready for use. Fig. 2 is a section at line x^2 in Fig. 1. Fig. 3 is a plan showing the sliding elements displaced. Fig. 30 4 is a cross-section at the guide-bar. Figs. 5 and 6 illustrate slightly-modified constructions, which will be hereinafter described.

Referring, primarily, to the principal figures, A A and B B are four devices which somewhat resemble combs and which for convenience I will call "combs." These four combs are substantially alike in form, having each a back and teeth. The combs A are fixed to a 35 guide-bar C, and the combs B, which alternate in position with the fixed combs, are adapted to slide on the bar C, the latter playing in a slot D, Fig. 2, in the solid back of the comb. Fig. 1 shows the normal disposition of the four combs, abreast or opposite. Each 40 comb has hinged to it at one end a cap E, adapted to be folded over, so as to house the ends of the teeth. In Fig. 2 the cap E is shown open or turned back in full lines and closed over the teeth in dotted lines. In 45 Figs. 1 and 3 some of the caps are represented as partly broken away.

G is a cord or the like threaded through

holes or apertures H in the combs, these latter being so disposed that when the parts are in the position seen in Fig. 1 the cord or lacing 55 will be zigzag.

The operation is as follows: The flat lock of hair is placed across the face of the device and pressed in, so as to engage the teeth of the combs. The caps E are then closed down 60 over the hair, so as to hold it in place, and the cord G drawn until it is straight, or nearly so, as in Fig. 3. The effect is to slide or move the combs B endwise to the position seen in said figure, thus producing a wave or edge- 65 wise zigzag in the incarcerated lock of hair. The surplus of cord G may now be wound about the device to bind the parts snugly and keep them in place.

The holes H are not essential to the successful operation of the device. The cord G may be made to engage the teeth of the combs, as indicated in Fig. 5, being placed before the lock of hair is made to engage the teeth, or the hole may be substituted by a notch H'. 70 (Seen in Fig. 6.) This enables the user to place the cord without the necessity of threading it through holes, as in the construction of the principal views.

The combs A and B may be made of any 80 suitable material—such, for example, as the materials from which combs are made. There may also be more or less of these combs in the device. I find four to serve very well.

So long as the alternate combs are slidable 85 longitudinally with reference to the others and the combs are all coupled or connected in a manner to form a single implement the requirements of my invention will be complied with.

I have called the device E for locking or holding the hair in the teeth a "cap," and it is herein shown as a cap hinged to the comb; but any similar bar or device to hold the hair down in the teeth of the comb may be employed as well. I do not limit myself in this 90 respect to the specific device shown.

One important feature in the construction of my device or implement is the transverse guide-bar, which connects the several combs 100 and unites them in one structure. This bar is disposed wholly between the extremities of the combs and avoids the necessity of a cumbersome handle and end frame, thus adapting

the implement to be worn without inconvenience to the user. The several devices for holding the hair in place are carried each by one of the combs.

5 Having thus described my invention, I claim—

1. An implement for the purpose specified, comprising a plurality of combs disposed side by side, spaced, and connected together by 10 a transverse guide-bar which traverses the combs between their extremities, the alternate combs being independently slidable longitudinally on said guide-bar with respect to the others which are fixed to the said bar, substantially as set forth.

2. An implement for the purpose specified, comprising a plurality of combs disposed side by side, spaced, and connected together by 20 a transverse guide-bar which traverses the combs between their extremities, the alternate combs being slidable independently with respect to the others, and covers carried by the respective combs for holding the hair in place, substantially as set forth.

25 3. An implement for the purpose specified, comprising a plurality of combs disposed side by side and spaced, a transverse guide-bar fixed to some of the combs and playing in

slots in the other and alternate combs, means hinged to the respective combs for holding 30 the hair in place, and a cord which engages the several combs for shifting the movable combs, substantially as set forth.

4. An implement for the purpose specified, comprising the fixed combs, the alternate, 35 slidable combs, a transverse guide-bar connecting the combs, and caps E, hinged to the respective combs for housing the ends of their teeth and holding the hair in place, substantially as set forth.

5. The combination to form an implement for the purpose specified, of the combs A and B, the guide-bar C, secured to the combs A and engaging slots in the combs B, the caps E hinged to the respective combs, and the cord 45 G engaging the several combs, for moving or shifting the combs B, substantially as set forth.

In witness whereof I have hereunto signed my name, this 20th day of March, 1902, in the 50 presence of two subscribing witnesses.

ANNIE SHERIDAN.
